Primary Examiner — Selina Sikder(74) *Attorney, Agent, or Firm* — Birch, Stewart, Kolasch & Birch, LLP(57) **CLAIM**

We claim the ornamental design for a remote control for air conditioner, as shown and described.

DESCRIPTION

FIG. 1 is a perspective view of a remote control for air conditioner showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a front elevation view showing a state of use thereof.
The broken lines in FIG. 8 are for environment purpose only and form no part of the claimed design.**1 Claim, 8 Drawing Sheets**(56)
